UNITED STATES PATENT OFFICE.

JOSEPH WESOLIK, OF BELLEVILLE, ILLINOIS, ASSIGNOR OF ONE-FOURTH TO EWALL LUETSCHER, OF BELLEVILLE, ILLINOIS, AND ONE-FOURTH TO LUDWIG KRIBBEN, OF CLINTON, MASSACHUSETTS.

COUPLER.

Original application filed August 27, 1923, Serial No. 659,471. Divided and this application filed January 26, 1925. Serial No. 4,752.

To all whom it may concern:

Be it known that I, JOSEPH WESOLIK, a citizen of the United States, residing in Belleville, in the county of St. Clair and 5 State of Illinois, have invented certain new and useful Improvements in Couplers, of which the following is a specification.

This invention relates to couplers and more particularly to mine car couplers.

10 This application is a divisional application of my application bearing Serial Number 659,471.

The object of this invention is to provide a coupler, which is a distinct and practical 15 improvement to overcome certain practical objections to, and defects in, mine car couplers of the present type.

A further object of the invention is to provide a male coupler having a jointed member 20 adapted for connection with a female, or mating coupler after one of the sections of the jointed member is moved from a right angular position to a horizontal position by one end thereof coming into contact with 25 a stationary post disposed in its path of travel.

A further object of the invention is the provision of means for holding the jointed member in horizontal alignment until 30 changed by actuating such means.

With the above and other objects in view, the invention consists in the novel features of construction, arrangement and combination of parts hereinafter more fully described and finally pointed out in the claims hereto appended.

Referring to the accompanying drawings forming a part of this specification, where in like characters of reference denote similar parts throughout the several views:

Fig. 1, is a plan view of a coupler embodying the features of my present invention.

Fig. 2, is a side elevation thereof.

Fig. 3, is a sectional view taken on line 45 3—3 of Fig. 2.

Fig. 4, is a view of the coupler, partly in side elevation and partly in vertical sec-

tional elevation with the locking mechanism shown as raised or unlocked to permit of the two coupling heads being disconnected. 50

Fig. 5, is a sectional view similar to Fig. 3, but showing the coupler heads in their engaged position which position they assume when two cars are bumped together.

Fig. 6, is a detail in side elevation of one 55 of the coupler heads showing the connecting bar thereof in full lines in one position and in dotted lines in another position.

It will be here observed that I have illustrated and described both a male and a female type of coupler in this application, as applied to opposite ends of mine cars, but the male coupler only being the subject matter of this application, as the female coupler is elected in my co-pending application 60 Serial Number 659,471, previously referred to, the female coupler being illustrated merely for the purpose of showing the relation of a female coupler to the male coupler and it is manifest that other types of female 65 couplers may be efficiently used with male coupler.

The male coupler comprises a head member designated 1 from which extends rearwardly a suitable draw bar 2. The sides of the head 1 extend laterally beyond the sides of the draw bar 2, as at 3 and the forward outer corners of the coupler head 1 are rounded, as at 4. The coupler head 1 and its integral draw bar 2 are provided with a 70 longitudinally disposed passage 5, which is open at its forward end. Slidably mounted in the passage 5 is a coupler bar 6, which is one section of a jointed member. The coupler bar 6 is provided with a longitudinally 75 disposed slotted opening 7 and the forward bifurcated end 8. A suitable stop pin 9 is suitably carried by the draw bar 2 and it passes through the slotted opening 7 of the 80 slidably coupling bar 6. The stop pin 9 prevents extreme forward movement of the 85 slidable coupler bar 6 during pulling movements thereof when connected with a female 90 and companion coupler.

A suitable connecting bar 10 is pivotally connected, by means of a pivot pin 11, at its rear end to the bifurcated end 8 of the slideable coupler bar 6. The forward end of the connecting bar 10 is provided with an upwardly directed pulling shoulder 12 and the lower corners thereof are rounded, as at 13 to facilitate coupling operations with a companion coupler. The reference numeral 14 represents a suitable L-shaped trigger member which is pivotally connected, by means of a suitable pin 15 to suitable bearings 16, which bearings 16 are suitably fixed to the top face of the coupler head 1 near its forward edge, as clearly shown in Figs. 1, 2, 4 and 6. The trigger 14 is provided with a vertically disposed downwardly directed trigger arm 17 having its forward lower corner rounded, as at 18. The arm 17 has its lower end face flat, as at 19 for engagement with the upper face of the rear end of the connecting bar 10, which is disposed in the bifurcated end of the coupler bar 6 for locking the connecting bar 10 in its extended or horizontally aligned position for coupling connection with a mating coupler head. The lower rear corner of the connecting bar 10 is concaved, as at 20, to engage and receive the rounded corner 18 of the trigger mechanism whenever the connecting bar 10 is moved into a vertically disposed or hanging position, as shown in full lines in Fig. 6, for shortening the overall length of the mine car when riding in a mine cage.

Each track leading from the mine cage is provided with a suitable striking post 21 which the connecting bar of the jointed member will strike after a mine car leaves a cage, thereby automatically raising the connecting bar 10 from its hanging or vertical position to a horizontally disposed position in alignment with its co-member, the slideable coupler bar 6, as shown in dotted lines in Fig. 6, and in full lines in Figures 1 to 5. The trigger 14 is provided with a rearwardly directed, horizontally disposed arm 22 which is provided at its rear end with a suitable hand operated lever member 23 which extends laterally to each side of a mine car where they can be easily and quickly raised by the operator for releasing the trigger arm 17 from engagement with the connecting bar 10 to permit the connecting bar 10 to fall or drop and assume a vertically disposed position, as clearly shown in full lines in Fig. 6. The draw bar of the coupler 1 is suitably connected to a mine car, as is manifest, and not believed necessary to illustrate, aside from dotted lines.

The female, or mating coupler, which is merely illustrated for the purpose of showing a complete coupled connection between two mine cars is shown as comprising a hollow coupler head 24 having a bottom wall 25, the side walls 26, the rear end wall 27

and the top wall 28. The front end of the female coupler 24 is open, as at 29 and the sides thereof are bounded by two opposed vertically disposed stop flanges 30 which are directed toward each other, as shown in Fig. 2, and the side walls 26 are also each provided with the bumping flange 31. The front outer corners of the bumping flanges 31 are rounded, as at 32 and the forward upper face of the bottom wall of the female coupler is beveled, as at 33.

A suitable lock plate 34 is positioned to the rear of the front openings 29 of coupler 24. The lock plate 34 is hinged by supported by means of a suitable pin 35, the ends of which pin extend into opposed vertically disposed slotted openings 36 in the side walls 26 of the female coupler to permit rearward arcuate movement of the lock plate and vertical movement thereof. The lower edges of the lock plate 34 are suitably arched, as at 37. The side edges of the lock plate 34, when in its vertically disposed position, engage the inner faces of the stop flanges 30 of the coupler 24 to prevent forward arcuate movement thereof.

The means for holding the lock plate 34 against accidental vertical displacement consists of a bail member 38. Arms 39 thereof are pivotally connected to the extended ends of the lock plate supporting pin 35. The bail member 38 is provided with a looped member 40, the lower portion 41 of which is adapted to engage either of the pair of stops 42 or 43 when the lock plate 34 is in its normally closed position, as will be apparent from Fig. 2, which prevents accidental vertical displacement of the lock plate 34.

The means for actuating the bail member and the lock plate for raising the latter from engagement with the connecting bar 10 of the male coupler, consists of a hand lever 44 extending toward both sides of a mine car and is journaled in bearings 45 fixed to the end of a mine car body. 46 represents a rod connecting the looped portion of the bail member with the operating hand lever 44. The forward end of the connecting rod 46 is looped, as at 47, and the lower portion of the loop midway its ends, as at 48, is lower than at its ends for releasing the lower portion of the loop from locked engagement with either stop 42 or 43 prior to lifting the lock plate 34 during an uncoupling operation with the jointed member of a male coupler. The coupler head 24 is provided with a rearwardly directed draw bar 49, as shown.

The operation of the coupler is as follows.

Assuming that two mine or other suitable cars are connected together, as clearly shown in Figs. 1, 2 and 4 and it is desired to disconnect the coupling connection there between, the operator raises the hand operated

lever 44 from either side of the car which first releases the lower portion of the loop portion of the bail member 36 from locking contact with either of the stops 42 or 43 and 5 brings the bail member to a substantial vertical position and then in its farther upward movement raises the lock plate 34 free of engagement or interference with the pull shoulder 12 of the coupler connecting bar 10 thereby permitting the two connected cars 10 to be uncoupled, as is manifest.

When it is desired to couple two cars together, the operator merely sees that the pivoted connecting bar 10 is raised to its 15 horizontally disposed position, as clearly shown in Figs. 2 and 4 and as the cars are moved together, the head of the connecting bar 10 strikes the lower portion of the lock plate 34 moving it suddenly in a rearwardly 20 and upwardly arcuate path until the pull shoulder 12 has moved into the coupler head 24 a sufficient distance to cause the lock plate 34 to automatically move back to its 25 normal vertical position by means of gravity, thereby automatically coupling the cars and locking the male and female coupler heads together.

Due to the large end opening 29 in coupler 30 head 24 and the pin like structure of the connecting bar 10, it is evident that the connected cars can move about a very sharp curve as indicated by connecting bar in dotted lines in Fig. 3.

It will be further observed from Fig. 5, 35 that when two cars are bumped together, that the coupler heads 24 and 1 come into end for end contact with each other, causing the coupler bar 6 and the connecting bar 10 to utilize the entire length of space provided 40 for within the two coupler heads and draw bar 2. The forward end of the connecting bar 10 at all times rests upon the bottom wall 25 of the coupler head 24 thereby preventing any possible chance of accidental 45 uncoupling of the coupling heads due to the fact that the pull plate or lock plate is locked against accidental vertical displacement by means of the bail member and its engaging stops.

50 It will be clearly apparent from the drawing and description of the male coupler that it can be effectively used with other types of female couplers than that illustrated and described in this application.

55 The many advantages of the herein described invention will readily suggest themselves to those skilled in the art to which it appertains.

I do not wish to be understood as having 60 limited myself to the exact details of construction shown and described, but desire to have it understood that the invention I have shown in the drawings is merely illustrative, as it is manifest that various minor 65 changes may be made in the form, shape and

particular arrangement of parts without departing from the spirit of my invention, hence I reserve the right to make any such changes, or modifications as may fairly fall within the scope of the appended claims 70 when fairly construed.

What I claim is:

1. In a coupler construction, a coupler head, a draw bar integral therewith having a bifurcated forward end, said head and draw bar having a longitudinal passage therein, a slideable member having a slotted opening therein mounted in said passage, a pin carried by the draw bar and passing through the slotted opening of the slideable member, a connecting bar pivotally connected to the bifurcated end of the slideable member, a jaw at the forward end of the connecting member, an angular trigger member pivotally supported by the coupler head with one arm thereof directed downwardly to engage the upper face of the rear end of said connecting bar to hold the bar in a horizontal coupling position and a handle connected to the other arm of the trigger for actuating the first mentioned arm of the trigger from contact with the connecting bar to permit the bar to fall by gravity to a perpendicular position.

2. In a coupler construction, a draw bar, a coupler head, said draw bar and head having a longitudinal passage open at the front face of the coupler head, a coupling bar having a vertically disposed slotted opening slidably mounted in said passage, a pin carried by the coupler head and passing through said slotted opening to limit the sliding movement of said coupling bar in either direction, a hook shaped connecting bar pivotally connected at its rear end to the forward end of said coupling bar, a trigger member pivotally supported upon the coupler head, a trigger arm directed downwardly from said trigger member for contact with the upper face of the connecting bar to hold the connecting bar in a horizontally extended position for coupling engagement with a companion coupler and a lever for actuating the trigger member for disengaging the trigger arm for engagement with the upper face of the connecting bar to permit the connecting bar to assume a vertically disposed position for sudden contact with a track post for automatically raising the connecting bar to its horizontal 110 coupling position.

3. In a coupler construction, a draw bar, a coupler head integral therewith and having a passage extending through the coupler head and into the draw bar, a coupler bar having a slotted opening therein slidably mounted in said passage, a pin passing through the draw bar and the slotted opening in said coupler bar to limit its sliding movement, a connecting bar pivotally con-

neeted at its rear end to the forward end of said coupler bar, a trigger member pivotally supported on the coupler head and engaging the connecting bar to the rear of the pivot point to hold the connecting bar in coupling position and a handle extending from the trigger member for actuating the

trigger member to release the connecting bar and permit it to swing into a perpendicular position.

In testimony whereof, I have hereunto signed my name to the specification.

JOSEPH WESOLIK.
